[57] CLAIM

The ornamental design for an aviator night vision imaging apparatus or similar article, substantially as shown and described.

DESCRIPTION

FIG. 1 is a front perspective view of an aviator night vision imaging apparatus showing our new design;
FIG. 2 is a rear perspective view;
FIG. 3 is a front plan view;
FIG. 4 is a top plan view; and
FIG. 5 is a side plan view.
The night vision imaging article is symmetrical and both sides appear the same.
